UNITED STATES PATENT OFFICE.

ROBERT C. BUCKLEY, OF PEORIA, ILLINOIS.

GANG-CULTIVATOR.

SPECIFICATION forming part of Letters Patent No. 674,755, dated May 21, 1901.

Application filed August 6, 1900. Serial No. 26,047. (No model.)

To all whom it may concern:

Be it known that I, ROBERT C. BUCKLEY, a citizen of the United States, residing at Peoria, in the county of Peoria and State of Illinois, 5 have invented certain new and useful Improvements in Gang-Cultivators; and I do hereby declare the following to be a full, clear, and exact description of the invention, such as will enable others skilled in the art to which 10 it appertains to make and use the same.

The object is to present a simply-constructed and efficient form of gang-cultivator adapted particularly for the cultivation of sugar-beets, although it is equally adapted in use for 15 the cultivation of other plants.

The invention consists in the novel construction and combination of parts of a gang-cultivator, as will be hereinafter fully described and claimed.

20 In the accompanying drawings, forming a part of this specification, and in which like letters of reference indicate corresponding parts, Figure 1 is a view in plan exhibiting a cultivator constructed in accordance with 25 my invention. Fig. 2 is a view in sectional elevation, taken on the line 2 2, Fig. 1; and Fig. 3 is a perspective detail view of a modification of one of the gangs detached from the structure.

30 Referring to the drawings, A designates an axle carrying the ordinary wheels a and having connected therewith shafts or thills B.

The axle A is designed to carry four gangs D, three being shown in this instance, although it is to be understood that the number may be increased or diminished, as found desirable or necessary. Each gang comprises two castings d, provided each with two slots d^2 d^3 , the slots d^3 being arranged at an angle 35 of about forty-five degrees with relation to the axle and the slots d^3 parallel therewith. These slots are designed to receive the shovels d^4 , one of which is indicated by dotted lines in Fig. 2, the shovels to be of any preferred construction, and by the disposition of the slots there will be ample space provided to permit passage between the aggrouped gangs of sticks, trash, and the like. These slots d^2 d^3 , in which the shovels are adjustably secured, are adapted by the arrangement 45 above described to permit of a variety of arrangements of the shovels with respect to

each other without varying in any way their angle of inclination to the direction of the progress of the cultivator. The castings are duplicates of each other, but are rights and lefts, and each is pivoted at its inner end to a bracket d^5 , bolted to the axle, the castings being so assembled that they can have no side motion. The gangs are connected with the brackets 55 by bolts or the like, whereby they may have a pivotal action to be raised or lowered, as desired. In order that the sections of each gang may be rigidly connected, an arch d^6 is employed, the same being of any preferred shape 60 in elevation—preferably A-shaped, as presenting the greatest strength and providing for suitable attachment for handles d^7 , by which each gang of the series may be raised or lowered. It is to be understood that each 65 of the gangs of the sets shown is of the same construction, so that a description of one will serve for all.

When the cultivator is in operation, the same is to be propelled over the ground by 70 means of horse-power, as usual, and the operator, standing at the rear, will, through the agency of the handles d^7 , be enabled to raise or lower, as may be necessary, any of the gangs, thus to cause the shovels to operate in 75 the most effective manner.

Fig. 3 shows in detail a modification of one of the gangs constructed according to my invention and detached from the axle. In this modification extension-strips are provided for 80 connecting the gangs with the bracket d^5 , so that by the use of such extensions the distance of the gangs from the axle, and consequently the leverage brought to bear by the operation of the handle, may be varied.

Having thus fully described my invention, what I claim as new, and desire to secure by Letters Patent of the United States, is—

1. In a gang-cultivator, the combination with a frame, of a gang secured to the frame, means connected to the gang for elevating and lowering the same, said gang being provided with straight slots arranged at an angle to each other, and cultivator-blades adjustably secured to said gang at the slots, whereby said 95 blades may be relatively adjusted without changing their angle of inclination to one another, or to the line of advance of the cultivator, substantially as described.

2. In a gang-cultivator, the combination with a frame, of a gang comprising two invertible and reversible members, means connected to the gang for elevating and lowering the same, and cultivator-blades adjustably secured to the gang, substantially as described.

In testimony whereof I affix my signature in the presence of two subscribing witnesses.

ROBERT C. BUCKLEY.
